UNITED STATES PATENT OFFICE.

DAVID NICKEL, OF MORRIS, ILLINOIS.

DOOR-HANGER.

SPECIFICATION forming part of Letters Patent No. 349,173, dated September 14, 1886.

Application filed June 29, 1886. Serial No. 206,639. (No model.)

To all whom it may concern:

Be it known that I, DAVID NICKEL, a citizen of the United States, residing at Morris, Illinois, have invented certain new and useful 5 Improvements in Door-Hangers, of which the following is a specification.

In the drawings, Figure 1 is a front elevation of my improved hanger, and Fig. 2 is a plan view of the same.

10 My improvement or invention relates more particularly to the method of attaching the depending portions of the hanger to the horizontal bar. Heretofore these two parts have been cast in one piece or fastened together 15 with rivets; but when cast the metal has been of course brittle and unable to endure the strains or shocks which sometimes occur, and when riveted together they have no means of preventing the racking and the consequent 20 wearing of the rivets and separation of the parts. To overcome these difficulties and objections I make the horizontal or rider bar A with shoulders or lugs B at the point of juncture with the depending portions C. These 25 shoulders are made at a proper distance apart to admit the depending portions of the hanger between them, so as to fit closely and snugly. This will be plain upon reference to Fig. 2 of the drawings. The parts are preferably pro- 30 vided with rivet-holes at their juncture, and a rivet is put through at each side of the

hanger and properly headed down, or other convenient means of fastening the parts together employed. The only office of these rivets is to prevent vertical displacement of 35 the parts and sustain the weight of the door. No lateral displacement can take place, as the shoulders on the rider-bar will prevent any tendency in that direction. By making my hangers in this way, channeled steel, or such 40 other metal as may be desired, may be employed for the depending portions of the hanger. No racking or lateral strain can affect the attachment of the parts at the rivet, and consequently all tendency to wear the same 45 laterally is obviated, and as the parts are only subjected to a straight downward pull, occasioned by the weight of the door, which weight is always steady and constant, no practicable wearing of the rivet can take place in that di- 50 rection.

What I regard as new, and desire to secure by Letters Patent, is—

In a door-hanger, the combination of a rider-bar provided with shoulders or lugs on its 55 side and depending portions fitted and fastened between such shoulders or lugs, substantially as described.

DAVID NICKEL.
